PENCIL

Eugen Wild, Pforzheim, Germany, assignor to
the firm Carl Emil Ruf, Pforzheim, GermanyApplication April 20, 1939, Serial No. 268,854
In Germany December 13, 1938

5 Claims. (Cl. 120—12)

This invention relates to pencils of the kind, in which the lead is advanced into writing position by pressing a button.

In pencils of the kind described the leads advanced into writing position are returned into inoperative position by pressing the button to release the lead, which is then pushed back into the sleeve by pressure exerted on the lead. When the lead is thus released, it is first imparted an advance movement whereby it will project farther from the point of the pencil. Consequently, when the forcing back of the lead is not effected with care, the lead may break. In any case this way of returning the lead requires several actions, i. e. pressing the button, pressing the point of the lead on the table or the like and forcing it back into the pencil by pressure.

It is an object of my invention to avoid breakage and loss of leads and to render the return movement simpler than was hitherto the case.

To this end, according to this invention, a single pressure device is made to advance into an operative position and return to an inoperative position alternately, a lead holder arranged in the pencil sleeve for axial displacement, the lead being adjusted in and advanced from the holder in any suitable manner, for instance by rotating a threaded spindle. The lead holder, when in either of the two end positions, is fixedly held therein.

In the drawings affixed to this specification and forming part thereof an embodiment of my invention is illustrated by way of example.

In the drawings

35 Figs. 1-6 are axial sections of the device along one pair of locking levers serving to alternately hold and release, the pencil holder;

Figs. 7-12 are similar views, however in the planes of another pair of locking and releasing levers,

40 Fig. 13 is a cross section on the line XIII—XIII in Fig. 1.

Figs. 1-2 and 7-8 illustrate the positions of the two pairs of levers in the inoperative position of the pencil holder, while Figs. 3 and 9 show them in the operative position,

45 Figs. 4-5 and 10-11 illustrate the positions of the two pairs of levers in the operative position of the pencil holder, while Figs. 6 and 12 show them in the inoperative position.

50 Referring to the drawings and first to Fig. 1, 1 is the outer jacket, 2 is the inner sleeve and 3 is an insert plate held near the end of the inner sleeve, while 4 is a tube fixed in the plate 3. 5 is the pencil holder, 6 being a self-closing

clamping head mounted at the writing end of the pencil holder. 7 is a threaded spindle projecting into the rear end of the pencil holder and serving to advance the lead 8. 9 is a pressure spring inserted between the insert plate 3 and a collar 12 fixed to one end of the slotted tube 10, which can be advanced in the jacket 1 by exerting pressure on the cap 11 closing the rear end of the jacket 1. 13 is a collar fixed to the rear end of the tube 10, which serves to guide same in the inner sleeve 2. The movable tube 10 is formed with four slits 14, 14 and 15, 15, extending from the collar 12 to the collar 13 and being arranged in pairs in diametrically opposite position. 16 and 17 is a pair of levers suspended, as shown in Fig. 7 by means of hooks 55 and 56, respectively, in radial notches of the collar 13, being secured therein by a ring 21 and projecting into the slits 14, 14 of the tube 10. The other pair of levers 18, 19 (Fig. 1) is formed with rounded link heads 20 22 projecting for oscillation into similarly shaped notches of the ears 24 formed on a guide piece 25 fixed to the pencil 5 and arranged for displacement in the slits 15 of the slotted tube 10.

20 In the movable tube 10 and on the lead holder 5 is further arranged a slide 26 formed with a wide collar 27 at the front end and with a narrow collar 28 at the rear end. 29 is a pressure spring encircling the slide 26 and pressing a flanged ring 31 against the collar 28.

25 The threaded spindle 7 projecting into the screw thread 32 of the lead holder 5 carries at its rear end a square head 33, which is guided for axial movement in a square sleeve 35 surrounded by a tubular sleeve 34 and fixed to the cap 11. 35 The tubular sleeve 34 rests with its conically contracted front end 30 against a conical seat 31 formed in a tube 36 forming an extension of the displaceable tube 10 projecting from the collar 13 and is enclosed in a sleeve 37 fixed to the tubular extension 36. It can be withdrawn from this sleeve together with the spindle 7 for the insertion of a fresh lead into the lead holder 5.

30 The advancing of the lead 8 in the lead holder 5 to make the point of the lead project from the clamping head 6 is effected by rotating the cap 11 exactly as in an ordinary pencil. On the other hand the advance and return of the pencil formed by the head 6, sleeve 5 and screw spindle 7 and the projecting of the head 6 and lead 8 from the point of the jacket 1 into writing position, and on the other hand the returning of the parts 6 and 8 into the inoperative position are effected by twice exerting pressure on the cap 11. 45 During the first pressing operation the pencil ad- 50 55

vances into writing position, after the second pressing operation it is returned into the inoperative position. These movements of the pencil 5 are brought about by the axially movable tube 10, which is acted upon by the spring 9, the slide 26 acted upon by spring 29 and the flanged ring 31 and the pairs of levers 16, 17 and 18, 19, as follows:

Following the first pressure exerted on the cap 11 the tube 10 and the flanged ring 31 of the slide 26 are advanced against the action of springs 9 and 29, until the projecting ledges 39 fixed to the rear end of the tube 4 (Fig. 7) adjoining the stops 40 formed in the slits 14 (Fig. 8). The pair of levers 16, 17 (Fig. 7) which is suspended from the collar 13 of the tube 10, accompanies this advance movement; in contrast thereto the pair of levers 18, 19 supported for oscillation in the guide piece 25 remains in its position of rest, until the flanged ring 31, meeting the projections 41 and 42 extending inwardly from the levers 18 and 19, respectively, causes these levers to spread against the action of leaf springs 46 fixed to the guide piece 25, the hook-shaped end 43 of lever 18 being withdrawn from behind the locking projection 44 formed on the tube 4 (Fig. 2). The flanged ring acts on the projection 41 of the lever 18 only so far that the oscillatory movement of lever 18 just suffices to disengage its hook-shaped end 43 from the locking projection 44, however not so far that also the second stop 45 is disengaged from the flange 27 of the slide 26. At this moment the compressed spring 29 of the slide 26 is free to expand and, since the flanged ring 31, forming the rearward abutment of the spring, rests against the stop 38 of tube 10, the front flange 27 of the slide 26 against the stop 45 of the lever 18, the levers 18, 19 which are forced inwardly by the leaf springs 46, and together with them the lead holder 5 fixed to the guide piece 25 are now advanced until the hook-shaped end 43 of lever 18 is forced inwardly by the leaf spring 46, being locked in front of the projection 44 (Fig. 3). The pair of levers 18, 19 and the clamping head 6 projecting from the jacket 1 by the advancing lead holder 5 are retained in their advanced position by the locking action of the lever 18 in coaction with the projection 44. In contrast thereto, when the pressure on the cap 11 is interrupted, the tube 10 is returned by spring 9 into its initial position together with the levers 16, 17 (Fig. 4). During this return movement the flange 12 of the tube slides over the front ends of these levers, securing them against outward spreading movement, so that the hook 43 of lever 18 is absolutely prevented from being released by the locking projection 44, so that by means of the guide piece 25 also the lead holder 5 and its head 6 are securely held in the writing position. Since now the slide 26 with its flanged ring 31 occupies the advanced position shown in Fig. 10, the lower ends 49 of the levers 16, 17, which follow the return movement of the tube 10, will not grip the flange 31 from below, but will retreat behind this flange, as shown in Fig. 10.

On the cap 11 being pressed for the second time, whereby the lead holder 5, head 6 and the advanced pair of levers 18, 19 are caused to be withdrawn again, the tube 10 and flanged ring 31 of the slide 26 are advanced again. In this case, since the slide 26 is now in advanced position, the advancing of the flanged ring 31 is carried out by the bottom ends 49 of the levers 16, 17 (Fig. 10). On the flanged ring 31 meeting

the nose 41 on lever 18, the hook-shaped end 43 of this lever is disengaged again from the locking member 44 (Fig. 5). Hereby the lever 18 and guide piece 25 are released and the flanged ring 31 which during its advance had engaged the nose 42 of lever 19, now pushes the guide piece 25 with the levers 18, 19 and with the lead holder 5 back into the inoperative position under the action of the compression spring 29 (Fig. 6), since the slide 26 abuts against the rear end of tube 10 and in consequence thereof the spring 29 can expand only rearwardly. The return movement of the flanged ring 31 under the influence of the spring 29 is not hindered by the levers 16, 17, for these levers, after the flanged ring 31 is advanced in front of the nose 42 on lever 19, have been spread outwardly by their noses 50 meeting the projections 51 on the guide piece 25 (Fig. 1), until the flanged ring 31 is free to return. After the return of the flanged ring 31, which carries the lever 19 along by its nose 42, the ring 31 is again positioned behind the bottom ends of the levers 16, 17 (Figs. 11 and 12). These levers are forced back into their initial position by an annular spring 52. After the cam face 53 on the inner side of the end of lever 19 has met the flange 27 of slide 26, thereby disengaging the nose 42 from the flanged ring 31 (Fig. 6), the slide 26 is carried back by the hook-shaped ends of the levers 16, 17, under the expansion of the spring 9 (on the second pressure being interrupted), into its initial position (Fig. 7), the noses 50 now resting against the projections 51 and causing the levers 16 and 17 to be spread outwardly, so that on pressure being exerted again on the cap 11, the flanged ring 31 is free to pass between the levers 16 and 17.

I wish it to be understood that I do not desire to be limited to the exact details of construction shown and described for obvious modifications will occur to a person skilled in the art.

I claim:

1. A pencil comprising in combination, a tubular outer shell or jacket, a lead holder arranged in said shell for axial movement, means comprising two pairs of levers suspended in said jacket for axial and rocking movement for locking said lead holder in said shell in two end positions, means axially displaceable on the rear end of said shell for exerting pressure on said locking means and a spring arranged to act on said locking means for causing said lead holder to advance into one and to recede into the other end position, respectively.

2. A pencil comprising in combination, a tubular outer shell or jacket, a lead holder arranged in said shell for axial movement, means comprising two pairs of levers suspended in said jacket for axial and rocking movement, means for locking said lead holder in said shell in two end positions, means axially displaceable on the rear end of said shell for exerting pressure on said locking means and a spring arranged to act on said locking means for causing said lead holder to advance into one and to recede into the other end position, respectively, one end of said spring abutting against the lead holder, while a member slidably on said lead holder abuts against the other end, and a pair of levers suspended from said member forming part of the means for locking the lead holder.

3. A pencil comprising in combination, a tubular outer shell or jacket, a lead holder arranged in said shell for axial movement, means comprising two pairs of levers suspended in said jacket

- for axial and rocking movement, means for locking said lead holder in said shell in two end positions, means axially displaceable on the rear end of said shell for exerting pressure on said locking means and a spring arranged to act on said locking means for causing said lead holder to advance into one end and to recede into the other end position, respectively, one end of the spring abutting against the lead holder, while a member 5
slidable on said lead holder abuts against the other end, a bearing fixed to said lead holder resting on said slideable member and a pair of levers suspended in said bearing forming part of the means for locking the lead holder.
- 10 4. A pencil comprising in combination, a tubular outer shell or jacket, a lead holder arranged in said shell for axial movement, means comprising two pairs of levers suspended in said jacket for axial and rocking movement, means for locking said lead holder in said shell in two end positions, means axially displaceable on the rear end 15 of said shell for exerting pressure on said locking means and a spring arranged to act on said locking means for causing said lead holder to advance into one end and to recede into the other end position, respectively, the locking means comprising two pairs of levers suspended in said jacket for axial and rocking movement, one lever of one pair being arranged to lock, the other lever of that pair being arranged to release the lead holder in one of its two end positions, while the 20 other pair of levers is arranged to hold and release, respectively, the lead holder in the other end position.
- 25

HUGEN WILD.
